UNITED STATES PATENT OFFICE.

HENRY F. BICKEL, OF PLAINFIELD, NEW JERSEY, ASSIGNOR TO THE NEW YORK AIR BRAKE COMPANY, A CORPORATION OF NEW JERSEY.

ANGLE COCK.

Application filed April 22, 1927. Serial No. 185,901.

This invention relates to air brakes and particularly to a special angle cock structure and related mechanism designed to preclude the occurrence of accidents such as have 5 heretofore been caused by the accidental or inadvertent closing of an angle cock between the locomotive and the train or between cars of the train.

Various arrangements have heretofore 10 been proposed to accomplish the same result. One proposal involves the elimination of the angle cocks altogether, but this is undesirable for the reason that if cars are uncoupled the brake pipe is completely 15 discharged and it requires considerable time to recharge the system with consequent serious delays in train schedules.

In the present invention, use is made of an angle cock of ordinary construction including 20 a handle arranged to latch it in both open and closed positions in conjunction with a by-pass valve which is operated by a pressure motor and which, if the angle cock is closed, will open to establish a by-pass 25 around the angle cock when pressure is supplied to the motor. This pressure is derived from a secondary pressure pipe which parallels the brake pipe, and may conveniently 30 be the signal pipe. This pipe is connected from car to car by hose couplings and is similarly connected to the locomotive and is 35 normally under pressure. The secondary pressure pipe is not equipped with angle cocks, so that when cars are disconnected it 40 is vented. If the angle cock is closed, as it normally would be at this time, the by-pass valve will immediately close as the result of the venting of the secondary pressure pipe.

If the pressure pipe is first disconnected 45 followed by the closing of the angle cock and disconnection of the brake pipe, the by-pass valve will close immediately upon closing of the angle cock. This last follows from the preferred arrangement in which the admission of pressure from the secondary pipe to the pressure motor which actuates the by-pass valve is under the control of the angle cock so that the flow is cut off when the angle cock is open.

50 This system entails the complete venting of the signal line when cars are disconnected, but the volume of air in the signal system is small and the recharging of the signal system requires a very brief interval. In 55 a system of this character the maintenance

of the secondary pressure pipe charged while the train is running is necessary to the operation of the by-pass valves, and accordingly, as a safety factor, provision is made to indicate, by the discharge of air 60 through a warning port in the cab, when the stop cock on the signal feed line is closed. This stop cock is characteristic of signal systems and is used to shut off the supply of air to the signal line. 65

A preferred embodiment of the invention is illustrated in the accompanying drawings, in which

Fig. 1 is a diagrammatic layout of the 70 brake pipe and signal line on the locomotive and the forward end of the connected vehicle in the train.

Fig. 2 is a transverse section through the stop cock through which the signal line is fed, showing the cock in closed position with 75 the warning port open.

Fig. 3 is a view similar to Fig. 2 showing the cock in opening position with the warning port closed.

Fig. 4 is a vertical axial section of the 80 improved angle cock showing this in open position with the by-pass valve closed.

Fig. 5 is a view similar to Fig. 4 showing the cock in closed position with the by-pass 85 valve open.

Referring first to Fig. 1, the main reservoir is shown at 11. This feeds air through a stop cock 12, strainer 13 and reducing valve 14 to a branch 15 of the signal line. This is connected to the signal pipe 16 90 through a stop cock of special form, indicated by the numeral 17 applied to its body. Pipe 15 is connected directly to the signal valve 18 which controls the action of the signal whistle 19. All the parts except the valve 17 are of ordinary construction and related in the usual manner.

The structure of the valve 17 is shown in Figs. 2 and 3. The port 20 is connected directly to the branch 15 and thus receives 100 air directly from the reducing valve. The port 21 is connected to the signal pipe 16. The port 22 is an atmospheric port through which the signal line at times is vented. The minute port 23 is the warning port leading 105 to atmosphere. The plug 24 of the cock is provided with two recesses 25 and 26 so disposed that in the closed position of the cock, shown in Fig. 2, the ports 20 and 23 are connected and the ports 21 and 22 are connected. 110

The effect is to vent the signal line and discharge air through a warning port 23 to indicate to the engineer that the signal line is cut off. In the open position of the cock 5 the warning port 23 is blanked, and the ports 20 and 21 are connected, allowing air to flow from the main reservoir 11 to the signal pipe 16 and charge the same.

At opposite ends of each vehicle, including 10 a locomotive, the portion of the signal line 16 carried by that vehicle terminates in flexible hose connections 27, each of which carries at its end a coupling 28, of the usual form, so that in a coupled train the sections 15 of the signal pipe 16 may be connected up to form a continuous signal line throughout the train. No angle cocks are provided on the signal line, but on the ends of each vehicle there are provided dummy couplings 20 29, by means of which the ends of the hose at the two ends of the train may be closed and properly supported.

The brake pipe 30 is as usual made up of sections carried by each vehicle in the train 25 and extending from end to end thereof, and at each end of each vehicle, with the exception of the forward end of the locomotive, there is provided an angle cock, indicated in Fig. 1 by the numeral 31 applied to its body. 30 At the forward end of the locomotive it is contemplated that an ordinary stop cock, indicated by the numeral 32, will be used, but as will be apparent, after consideration of the specification, a special angle cock 31 35 might be substituted for the cock 32 if desired. It is not ordinarily considered necessary.

The various sections of the brake pipe 30 are connected throughout the train by flexible hose 33 interposed between the angle cocks of adjacent vehicles and connected together by the usual separable couplings 34. At each end of each vehicle dummy couplings 35 are provided to close the ends of 40 the brake pipe and to support the flexible hose, but are used only at the ends of the train.

The dummy couplings 29 and 35 above referred to are necessary elements of the system, first because the signal pipe has no angle cocks, and second because the angle cocks 31 are by-passed, as will later be described, under normal operating conditions, so that some other means must be provided to close 55 the ends of the brake pipe at the two ends of the train.

Turning now to Figs. 4 and 5, the structure of the special angle cocks will be described in detail.

60 The body 31 of the cock is provided with a tapped opening 36, which receives the end of the brake pipe 30, and a tapped opening 37, to which the hose section 33 is attached.

65 Mounted in the body 31 is a ported bushing 38 in which turns a plug 39 of the cock

which has a through port 40. In one position of the cock this port establishes communication from the threaded opening 36 to the threaded opening 37, and in a position approximating 90° thereto the plug 70 interrupts the aforesaid communication. The plug may be turned from one to the other of the above positions and latched in either position by a latching handle 41 of ordinary construction.

75 Formed in the bushing 38 are two adjacent ports 42 and 43 which, in the open position of the cock plug 39, are blanked by this plug (see Fig. 4), and which, in the closed position of the cock plug 39 (see Fig. 5), are connected by recess 44 formed in the plug 39. Passage 45 leads to the port 42 and terminates in a threaded recess 46 which receives a pipe 47 (see Fig. 1) connected directly to the signal pipe 16. Passage 48 leads from the port 43 downward through the body 31 and through an auxiliary body 49 bolted to the lower portion thereof. Formed in the lower portion of the body 49 and closed by a cap 51 is a cylinder having a cylinder bushing 52 in which works a piston 53 sealed by a piston ring 54 and also by a cup leather 55. The port 49 leads to the space below the piston. The piston is mounted on the lower end of a shouldered rod 56 and is held thereon by a nut 57 which engages retaining plate 58 for the cup leather 55. A shoulder 59 on the rod 56 instead of bearing directly upon the upper face of the piston 53, engages a sealing gasket 61 mounted in a recess in the piston 53 and designed to seal against the lower rim of a bushing 62 mounted in the body 49 at the upper end of the cylinder.

70 The space above the piston 53 is vented to atmosphere by port 63. The rod 56 carries at its upper end a piston valve 64 having three piston rings 65, 66, 67. The piston 64 carries on its lower face a gasket 68 which in the lower position of the piston seals on a rim on the upper end of the bushing 69 through which the rod 56 slides. An equalizing port 71 extends through the piston. The piston works in a cylinder bushing 72 fixed in an upward cylindrical extension 73 of the body 49. This extension enters a recess formed in the lower portion of the body 31 and is closed and sealed at its upper end by a threaded plug 74. The plug 74 serves as a spring seat for the spring 75 which holds the tapered cock plug 39 in position and also for a spring 76 which urges the valve 64 and piston 53 downward. The bushing 72 is formed with ports 77 and 78 which are not aligned, but are so arranged that when the piston 64 is in its lowermost position the port 77 is between the piston rings 65 and 66 and the port 78 is between the piston rings 66 and 67. The port 77 communicates by passage 79 with the threaded opening 36 and

the port 78 is connected by a passage 81 with threaded opening 37.

From the above description it will be observed that whenever the cock plug is closed (see Fig. 5) the space below the piston 53 is in direct communication with the signal pipe 16, so that if the signal pipe be under pressure, as is assumed to be the case in Fig. 5, the piston 53 will be moved to its uppermost position so that the piston valve 64 clears the ports 77 and 78 and allows them to communicate with each other establishing a by-pass around the cock plug by way of the passages 79 and 81 and the space within the cylinder bushing 72.

The operation of the device will now be readily understood. If a train is connected and the signal line is under pressure, it is practically immaterial whether the angle cock, indicated generally in Fig. 1 by the numeral 31, be open or closed, for if closed the pressure in the signal pipe acting on the piston 53 will open the by-pass valve 64.

Assuming it is desired to uncouple a locomotive from a train or divide a train, the engineer turns valve 17 to vent the signal line. The angle cocks are then closed and the brake pipe hose disconnected.

The engineer of a train equipped with angle cocks of this improved type is assured that if the signal line is charged the brake pipe cannot be interrupted by the accidental closing of an angle cock. The warning port in stop cock 17 minimizes the chance of oversight as to the condition of the signal pipe.

In the above description specific reference has been made to the signal pipe, but obviously any pipe which parallels the brake pipe and which is normally charged while the train is in operation, will serve the purpose. Consequently, while the particular embodiment described is considered the best under present conditions, I recognize that the invention is not limited necessarily to the use of the signal pipe, provided some equivalent pressure conveying pipe be available.

What is claimed is,—

1. The combination with a fluid pressure brake system including a brake pipe and an angle cock controlling the brake pipe; of a secondary pressure pipe; and pressure actuated valve means connected with said secondary pipe and controlling a by-pass around said angle cock, the arrangement being such that the by-pass is closed unless said secondary pipe is under pressure.

2. The combination with a fluid pressure brake system including a brake pipe and an angle cock controlling the brake pipe; of a secondary pressure pipe; and pressure actuated valve means controlling a by-pass around said angle cock and subject to concurrent control by the pressure in said sec-

ondary pipe and by the position of said angle cock in such manner that the by-pass is closed except when the angle cock is closed and the secondary pipe is at the same time under pressure.

3. The combination in a fluid pressure brake system, of a brake pipe; an angle cock controlling the brake pipe, and having supplemental valve ports isolated from the brake pipe and arranged to move from non-registering to registering relation when the cock moves from open to closed position, and vice versa; a secondary pressure pipe; a valve controlling a by-pass around said cock; a pressure motor for actuating said valve; and connections establishing communication between said secondary pipe and motor through said supplemental ports.

4. The combination in a fluid pressure brake system of a brake pipe; an angle cock controlling the brake pipe, and having supplemental valve ports isolated from the brake pipe and arranged to move from non-registering to registering relation when the cock moves from open to closed position, and vice versa; a secondary pressure pipe; a valve controlling a by-pass around said cock; an abutment operable by fluid pressure to move said valve in an opening direction; means urging said valve closed; and connections controlled by said secondary ports and arranged when said ports register to admit pressure fluid from said secondary pipe against said abutment.

5. In an angle cock, the combination of a body formed with main air passages and a seat for the cock plug, there being auxiliary ports in said seat isolated from said air passages; a cock plug in said seat having a main air passage and auxiliary ports, so arranged that the auxiliary ports are out of register with those in the seat only when the main air passages of plug and seat are in communication with each other; a valve controlling a by-pass between the air passages of said body around said cock plug; means urging said valve closed; a pressure-operable abutment for forcing said valve open; and connections controlled by said auxiliary ports for admitting pressure fluid against said abutment.

6. In an angle cock, the combination of a body formed with main air passages and a seat for a cock plug; a tapered cock plug in said seat; a spring serving to urge said cock to its seat; a second body removably mounted on said cock body and serving as a seat for said spring; and a by-pass valve with connected pressure motor mounted in said second body and controlling a by-pass around said cock plug.

In testimony whereof I have signed my name to this specification.

HENRY F. BICKEL.
